UNITED STATES PATENT OFFICE

HERBERT L. SARGENT, OF SALEM, MASSACHUSETTS

TORSIONAL PENDULUM DRIVE

Application filed December 6, 1930. Serial No. 500,603.

My invention relates to reliable apparatus for operating torsional pendulums and while not limited thereto is especially adapted to operate torsional pendulums used as advertising devices for the window display of commodities.

In carrying my invention into effect I provide a small electric motor and a driving connection between the motor and torsional pendulum whereby the rotary motion of the motor is converted into an oscillatory turning motion for maintaining the pendulum in operation.

The features of my invention which are believed to be novel and patentable will be pointed out in the claims appended hereto. For a better understanding of the invention reference is made in the following description to the accompanying drawings which show in Fig. 1 a general view of the invention as applied to the operation of a torsional pendulum advertising device. Fig. 2 shows a perspective detail view of the driving mechanism between the motor and pendulum; and Figs. 3 and 4 show detail views of a portion of this mechanism in different operating positions.

The advertising device represented in Fig. 1 comprises a platform 10 upon which various commodities may be placed for display purposes. The platform is supported by suspension members 11 from the lower end of a flat steel strip 12 the upper end of which is fastened to a stationary support 13. It will be evident that if the platform is given a turn in one direction the parts will oscillate as a torsional pendulum due to the torsional spring action of the flat steel portion 12. The character of the oscillations will depend upon the length of part 12, the weight on the platform, etc. However, such oscillations will soon die out and the platform will come to rest in a neutral position unless some external oscillation retaining force is applied thereto at the proper time and di-

rection. The force necessary to apply to maintain the pendulum in operation at its natural oscillation period is small and is supplied in accordance with my invention by a small electric motor operating on the 50 pendulum mechanism, a preferred form of which is shown in Fig. 2.

Referring to Fig. 2 the stator of the electric motor is shown at 14. This motor may be most any type of self-starting rotary motor designed to be continuously energized without injury should it become stalled.

I have obtained satisfactory operation using the type of motor described in United States Patent No. 1,283,435, October 29, 1918, 60 to Warren. Such a motor is self-starting and may be continuously energized without injury even when stalled. It consumes small current and when its speed is reduced by gears furnishes enough power for the purpose in question. In Fig. 2, 15 represents a casing containing reduction gears between the motor and a crank arm 16 which is driven from the motor at a slow speed in a clockwise direction. At the outer end of this crank 70 arm is a member 17 pivoted to the arm at 18. Member 17 is secured to a rod 19 which is pressed through 17 at right angles to the plane of rotation of arm 16. Rotation of the pivoted member 17 about pivot 18 is limited 75

in one direction by the stop pin 20 and is normally restrained from movement in the other direction by a spring 21 fastened between the rear extension of rod 19 and the hub of crank arm 16. The torsional spring 12 is hung from the common support 13 a few inches above and in front of the crank arm 16 and extends downward in alinement with the axis of rotation of the crank arm. An arm 22 is fastened to the torsional member 12 a few inches below the axis of crank arm 16 much nearer the upper than the lower end of member 12. Arm 22 is at right angles to the torsional member and when the latter is in a natural position arm 22 extends toward 80 85 90

crank 16. Near the outer end of arm 22 is secured an upwardly extending rod 23 and a block 24 in which both rods 23 and 19 may slide, fastening these rods together in driving relation. Thus block 24 may slide horizontally on rod 19 and vertically on rod 23. This swivel arrangement converts the rotary movement of crank 16 into an oscillatory movement of arm 22 in planes at right angles to each other. The oscillatory movement of arm 22 is thus conveyed to the torsional pendulum spring 12 for the purpose of supplying sufficient energy to keep the torsional pendulum in operation after it is started.

15 If crank 16 and arm 22 revolved continuously at the same uniform speed their component movements in the same horizontal direction would vary according to a sine law. While the crank arm 16 tends to revolve at 20 a uniform speed it is of course impossible for arm 22 to do so or to have a horizontal component movement parallel to arm 16 which varies as a sine law. This is because arm 22 must slow down, stop and reverse its direction at the extremity of each oscillation.

In order to transfer beneficial horizontal motion from one part to the other for the purpose in question it is therefore necessary to bring their laws of movement in the common 30 direction into coincidence or in phase, so to speak, or else provide a flexible tie between the parts that will permit relative horizontal movement in the same direction. This is accomplished in part by allowing a variation in 35 speed (including zero speed) of motor 14 and in part by the flexible connection afforded by the pivoting of member 17 on arm 16. The flexible connection between rod 19 and arm 16 by reason of having part 17 40 pivoted at 18 is made use of at the extremities of the oscillation of the torsional pendulum to stall the driving motor momentarily while the torsional pendulum is reversing. Energy is absorbed by spring 21 in bringing 45 the torsional pendulum to a stop and is given out again in starting the torsional pendulum in the reverse direction. Thus the torsional pendulum is reversed quicker than would otherwise be the case and a more lively movement of the advertising display is obtained.

To accomplish these results pins 25 are provided on opposite diameters of the path of movement of arm 16, which pins extend into the path of movement of the outer 55 hooked end of the hinged member 17. As arm 16 rotates opposite these pins 25 the hook in member 17 engages the pins near the extremity of the swing of the torsional pendulum. The motor 14 is stalled while the 60 momentum of the torsional pendulum carries arms 23 and 24 outward sufficiently to turn member 17 on its pivot against the tension of spring 21 as represented in Fig. 3. The parts are adjusted so that the hook member 17 is released by pin 25 just before or as

the torsional pendulum reaches its extreme movement and stops. The motor 14 in the meantime has moved arm 16 slowly to the extent permitted by the unhooking action just described. The position of the parts at this 70 stage is substantially as represented in Fig. 4. Spring 21 now slowly pulls the hook 17 back into the position shown in Fig. 2 against stop 20 accelerating the torsional pendulum in its new direction of movement. This 75 stalling and slow movement of the motor at the extremities of the swing of torsional pendulum and the speeding up of the reversing of the torsional pendulum corrects the phase relation between the two parts or allows the 80 torsional pendulum to catch up in phase, so to speak, with crank arm 16. As the hook 17 comes back into the position shown in Fig. 2 and the torsional pendulum increases in speed the speed of motor 14 increases and supplies 85 energy to accelerate the pendulum, the parts now moving together through the swivel block 24, said block moving downward on rod 23 and toward 16 on arm 19 as the arm 19 moves through the first quadrant of the 90 lower portion of its swing. The parts thus move in phase until the opposite extremity of the pendulum swing is reached, where the same operation is repeated as hook 17 engages the left hand pin 25 with the arm 16 95 moving in an upward direction. Thus each revolution of crank 16 corresponds to a complete oscillation of the pendulum, and alternate half revolutions of arm 16 corresponds to consecutive movements of the pendulum in 100 opposite directions.

As represented in Fig. 2 the angle of swing of the torsional pendulum at the point where arm 22 is attached is slightly less than 180 degrees. The platform 10 however may turn 105 through a much larger angle depending upon the length of member 12 below arm 22, the weight of platform 10, etc. and these factors will determine the reversal period and the length of time the motor is stalled.

The energy necessary to keep a torsional pendulum in operation is very small. I have found that a motor having an input of less than 1/100000 horse-power will maintain a pendulum having a platform weight of 100 110 pounds in constant oscillation in the manner and by the apparatus herein described. The apparatus establishes a definite phase relation between the motor and pendulum for short intervals of time during the swing of 115 the pendulum in either direction and adds sufficient energy thereto to overcome friction, etc. and maintain the pendulum in oscillation after it is started.

To add to the attractiveness of the display 120 I may provide a lamp as indicated at 26 for illuminating the table. The lead 27 for the lamp may be supported on the pendulum strip 12 so as not to interfere with the operation and be attached to the same outlet indi- 125

cated at 28 which supplies the electric motor 14. The lead may be extended to the table as indicated at 29 in order to operate electrical devices, such as the electric clock represented at 30, displayed on the oscillatory table.

Various different arrangements for conveying motion from the electric motor to the torsional pendulum will occur to those skilled in the art and I do not wish to be limited to the particular arrangement described but seek claims commensurate with the scope of the invention.

What I claim as new and desire to secure 15 by Letters Patent of the United States, is:—

1. A torsional pendulum, a self-starting rotary motor, and motion transmitting driving means connected between the motor and pendulum for imparting energy from the motor to the pendulum in both directions of oscillation of the pendulum to maintain the pendulum in operation after being started.

2. A torsional pendulum, a self-starting continuously energized, rotary electric motor, and motion transmitting driving means between said motor and pendulum for imparting energy from the motor to the pendulum in both directions of oscillation of the pendulum for maintaining the latter in oscillation after it is started.

3. A torsional pendulum, a self-starting rotary electrical motor, said motor being continuously energized and designed to withstand continuous energization without injury when stalled, a motion transmitting driving connection between said motor and pendulum which permits the motor to drive the pendulum in both directions of its oscillatory movement and causes the motor to be stalled at the extremities of the oscillation of the pendulum when its motion is reversing.

4. A torsional pendulum, a rotary electric motor for maintaining said pendulum in operation after being started, said motor being self-starting, continuously energized and capable of being stalled without injury, and means connected between the motor and pendulum for transforming the rotary motion of said motor into the oscillatory motion of 50 said pendulum, said means causing the stalling of said motor when the motion of the pendulum is reversing at the extremities of its oscillation.

5. A torsional pendulum, a motor, a crank 55 rotated in a vertical plane in one direction only by said motor, an arm extending horizontally from said pendulum, a driving connection between said crank and arm whereby rotary movement of the crank is converted into an oscillatory movement of said arm for maintaining said pendulum in operation after it is started, and lost motion means in said driving connection for stopping the crank arm each half revolution in 60 substantially horizontal positions when the

pendulum is reversing at the extremities of its oscillatory movement.

6. A torsional pendulum, a rotary motor, a crank having a horizontal axis of rotation at right angles to the axis of oscillation of 70 the pendulum, and means connecting said crank and pendulum for causing a complete oscillation of said pendulum for each revolution of said crank, the two horizontal positions of the arm corresponding to the extremities of oscillation of the pendulum, said motor and connection serving to maintain said pendulum in oscillation after it is started.

7. A torsional pendulum, a rotary motor 80 having a crank arm, with its axis of rotation horizontal and at right angles to the axis of oscillation of the pendulum, a member pivoted on a horizontal axis at the outer end of the crank, a horizontal rod extending from said member toward the pendulum, a horizontal arm extending from the pendulum toward the crank, a vertical rod carried at the outer end of said arm, said horizontal and vertical rods being connected by a block 85 slideable on both rods, said arrangement forming a driving connection between the motor and pendulum to maintain the latter in oscillation after it is started, the two horizontal positions of the crank corresponding to the 90 two extremities of the oscillation of the pendulum, means for engaging the pivoted member when the crank is in substantially horizontal positions to stop the motor, said pivoted member then being turned on its pivot 95 to release the crank by the momentum of the pendulum as it approaches the extremities of its oscillations, and a spring resisting such turning of the pivoted member and serving to accelerate the pendulum in the opposite 100 direction and restore the pivoted member to its original position after the crank has been released.

8. A torsional pendulum, a motor for supplying energy to maintain said pendulum in oscillation after being started, a crank operated by said motor, a driving connection between said crank and pendulum whereby alternate half revolutions of the crank corresponds to the successive movements of the 110 pendulum in opposite directions and each complete revolution of the crank corresponds to a complete oscillation of the pendulum, said driving connection maintaining a definite phase relation between the movement of the crank and pendulum except when the pendulum is reversing at the extremities of its oscillations, and means for momentarily stopping the rotation of the crank as the pendulum approaches the extremities of its oscillations.

9. A torsional pendulum comprising a long flat metallic suspension member secured at its upper end and supporting a weight at its lower end, a self-starting rotary electric 130

motor, a driving connection between said motor and the suspension member connected to the latter at a point nearer its upper than its lower end for converting the rotary motion of said motor into an oscillatory motion of said pendulum for supplying energy to the pendulum for both directions of its movement to maintain said pendulum in oscillation after being started.

16 In witness whereof, I have hereunto set my hand this first day of December, 1930.
